MANIFOLDING PILE

Carl W. Brenn, Montclair, N. J., assignor to Autographic Register Company, Hoboken, N. J., a corporation of New Jersey

Original application March 22, 1930, Serial No. 438,063. Divided and this application March 12, 1937, Serial No. 130,449

6 Claims. (Cl. 282—12)

This invention relates to manifolding means, and more particularly, to a manifolding pile comprising a plurality of superposed continuous worksheet strips and a continuous carbon sheet strip interposed between each two adjacent worksheet strips.

Heretofore, it has been suggested that the carbon sheet strip be held captive in the pile against lateral shifting movements and that the worksheet strips of the pile be held together in registration by securing means such as staples extending through all of the strips of the pile.

In cases where it is merely desired to hold the carbon strip to the worksheet strip, it was proposed to employ spots of gum between the adjacent faces of the carbon strip and worksheet strip.

An object of this invention is to provide a manifolding pile in which the worksheet strips are held together surface-to-surface in registration by means which, while it does not engage the carbon strip, does, however, hold the carbon strip captive in the pile against excessive lateral movement.

It is a further object of this invention to so provide the manifolding pile just described that the carbon is held captive between the worksheets both before and after the pile of strips is severed into form-lengths, which operation may be facilitated by transverse perforations in the worksheet strips located between form-lengths, as has been done heretofore.

This application is a division of my copending application Serial No. 438,063, filed March 22, 1930; and according to the invention of the present application the objects aforesaid are attained by providing a carbon strip which is apertured at intervals along the length of the same, with these apertures in the form of marginal cut-outs or notches completely displaced from a transverse tear-off line. Such cut-outs provide zones of face-to-face direct contact between adjacent worksheet strips, so that these strips may be secured together by suitable securing means located in said zones of direct contact.

In the accompanying drawing:

Figure 1 is a perspective view of a manifolding strip made in accordance with the present invention.

Fig. 2 shows a length of said pile, laid out flat. The manifolding pile shown in the exemplifying embodiment illustrated in the drawing comprises a plurality of continuous worksheet strips 10, of which there may be two or more, having a succession of printed forms or form-lengths 11

which are divided by lines of perforations 12. Interposed between each two adjacent worksheet strips 10 is a carbon strip 13. If desired, the pile may be folded zig-zag fashion to form a block or pack as shown and the folds may preferably occur on the lines of perforations 12. After a set of forms 11 has been written upon, it is usually severed from the rest of the pile along the lines of perforations 12, whereupon the forms 11 may be separated from each other and from the intervening carbon sheets 13a formed by tearing, to be distributed as desired, or the booklet of forms 11 and carbon sheets 13a may be left intact to receive subsequent writing or notations. The device of the present invention is particularly advantageous when the latter method is employed, for by it the carbon sheets 13a are held captive between the worksheets or forms 11 so that writing on the uppermost form of the booklet will be reproduced on the under forms 20 by the carbon or other transfer material.

Heretofore, it was proposed to fasten the strips together so as to hold the carbon strip captive between the worksheet strips by adhesive applied to the edges of the strips of the pile when the pile is compressed. It was also proposed to secure all of the strips, including the carbon strip or strips, together by staples passing through all of the strips. It was also proposed to hold the carbon strips against shifting relative to the worksheet strips by spots of gum or other adhesive material located between the adjacent faces of the worksheet strips and the carbon sheet strips. This latter proposal has the advantage of permitting the securing means to be applied while collating the worksheet strips and carbon strips, but it has the disadvantage of not holding the worksheet strips in the pile together against lateral shifting movement relative to each other.

According to the present invention, the advantage of being able to apply the securing means during the process of collating the worksheet and carbon sheet strips is retained, but in addition the securing means also serves the function of holding the worksheet strips against lateral shifting movements relatively and yet permits the carbon strip to be entirely free of adhesive material and avoids subjecting the carbon strip to pressure which is applied to cause the worksheet strips to adhere together or to be secured together by a staple, thus avoiding the marking of the face of the under worksheet as a result of this pressure.

This is accomplished, according to the present invention, by so shaping the lateral margin or margins of the carbon strip at spaced points 55

along the length thereof to provide notches 14 defining zones 15 of face-to-face direct contact of the adjacent worksheets with each other, and by locating the adhesive, staple or other worksheet strip securing means in these zones of direct contact.

In the form of the invention illustrated in the drawing, the carbon strips 13 are shown as of the same width as the worksheet strips 10, and with 10 the lateral edges of all the strips in registration, and the notches 14 spaced along both margins of a carbon strip 13.

The securing device for attaching the worksheet strips together in these zones 15 are shown 15 as spots 16 of adhesive, applied to adjacent faces of adjacent worksheet strips 10.

When the notches 14 and the securing means 16 are placed at both lateral margins of the pile as shown, the carbon strip 13 is held against substantial lateral shifting movement, and yet, in 20 a booklet comprising a set of forms 11 and interleaved carbon sheets 13a is severed from the pile, the carbon sheets 13a are held in the booklet against casual removal by the tongue-like portions 25 17 of a carbon sheet which extend between the notches 14 and the adjacent end 18 of the carbon sheet.

If it is of prime importance that the worksheet strips be held together and unimportant that 30 carbon strips be held captive in the pile against all lateral movements, as might sometimes be the case, the zones 15 may be provided at only one side edge of the pile, leaving the other side of the pile open for easy removal of the carbon 35 sheets 13a from between the worksheets of the booklet resulting from the tearing off of a set of forms.

Preferably, the zones 15 and the adhesive spots 16 are so dimensioned that when the worksheet 40 strips are affixed together, the carbon strip 13 is not engaged by the adhesive and is entirely unaffixed to the worksheet strips so as to be easily separated from the worksheet strips when the written booklet of forms 11 and carbon sheets 45 13a have been severed from the pile, and, after that, it is desired to separate the different sheets of the booklet.

The cut-outs 14 which provide the zones 15 of direct contact of the adjacent worksheet strips 50 10 with each other, are placed at intervals along the pile, and at least one in each form, and these cut-outs, while between the severance lines 12, are wholly beyond any such line, so that the worksheets may be held together by the securing 55 means after a set of superposed forms has been severed from the pile.

It should also be understood that by having the securing means located in a portion of the pile uncovered by the carbon strip, pressure may 60 be employed in applying the securing means, for instance, the gum spots 16, without that pressure causing the underlying worksheets to be marred or soiled by carbon from the carbon strips.

The use of spots of adhesive material is usually 65 preferred for the usual manifolding work such as in ordinary typewriters, since the gum or adhesive may be of a kind having the characteristics of easily being pulled off the paper or of splitting readily. When adhesive is used, typographical 70 errors may be easily erased on the carbon copies by separating the sheets by merely pulling them apart while they are on the typewriter platen, and then folding back the upper worksheet and carbon strips while the erasure is being made on 75 the lower worksheet strip.

The zones 15 for the securing means may be placed wherever directed in the forms, for instance, as shown, at the tops of the forms.

Variations and modifications may be made within the scope of this invention, and portions 5 of the improvements may be used without others.

I claim:

1. A manifolding pile comprising a plurality of continuous worksheet strips and a continuous carbon strip interposed between adjacent worksheet strips, said strips having transverse lines of severance at form-lengths along which the pile may be severed, thereby producing a set of worksheets and interleaved carbon sheet or sheets, the carbon strips being of substantially the same 15 width as the worksheet strips and having cut-outs at both lateral margins and located at sheet-length intervals along the pile to provide zones of face-to-face direct contact of the adjacent worksheet strips with each other; and means 20 located in said zones of direct contact for securing the worksheet strips together at both lateral margins, said cut-outs and means located therein being both wholly located between the lines of severance to hold the worksheets of a severed set 25 in registration and to hold the carbon sheets captive between the worksheets.

2. A manifolding pile comprising a plurality of continuous worksheet strips and a continuous carbon strip interposed between adjacent work- 30 sheet strips, said strips having transverse lines of severance at form-lengths along which the pile may be severed, thereby producing a set of worksheets and interleaved carbon sheet or sheets, the carbon strips being of substantially the same 35 width as the worksheet strips and having cut-outs at both lateral margins and located at sheet-length intervals along the pile to provide zones of face-to-face direct contact of the adjacent worksheet strips with each other; and means lo- 40 cated in said zones of direct contact for securing the worksheet strips together at both lateral margins, said cut-outs and means located therein being located between the lines of severance leaving strip material at each side of said means to 45 hold the worksheets of a severed set in registration and to hold the carbon sheets captive between the worksheets.

3. A manifolding pile comprising a plurality of continuous worksheet strips and a continuous 50 carbon strip interposed between adjacent worksheet strips, said strips having transverse lines of severance at form-lengths along which the pile may be severed, thereby producing a set of worksheets and interleaved carbon sheet or sheets, the 55 carbon strips being of substantially the same width as the worksheet strips and having cut-outs at both lateral margins and located at sheet-length intervals along the pile to provide zones of face-to-face direct contact of the adjacent 60 worksheet strips with each other; and spots of adhesive material located in said zones of direct contact for securing the worksheet strips together at both lateral margins, said cut-outs and spots of adhesive material located therein being both wholly located between the lines of severance 65 to hold the worksheets of a severed set in registration and to hold the carbon sheets captive between the worksheets.

4. A manifolding pile comprising a plurality of 70 continuous worksheet strips and a continuous carbon strip interposed between adjacent worksheet strips, said strips having transverse lines of severance at form-lengths along which the pile may be severed, thereby producing a set of work- 75

5 sheets and interleaved carbon sheet or sheets, the carbon strips being of substantially the same width as the worksheet strips and having cut-outs at both lateral margins and located at sheet-length intervals along the pile to provide zones of face-to-face direct contact of the adjacent worksheet strips with each other; and spots of adhesive material located in said zones of direct contact for securing the worksheet strips together at both lateral margins, said cut-outs and 10 spots of adhesive material located therein being located between the lines of severance leaving strip material at each side of said means to hold the worksheets of a severed set in registration 15 and to hold the carbon sheets captive between the worksheets.

6. A manifolding pile comprising a plurality of continuous worksheet strips and a continuous carbon strip interposed between two adjacent 20 worksheet strips, said strips being separated into form-lengths by weakened lines of severance extending transverse to the pile, the carbon strip having apertures arranged at intervals there-

along to provide zones of direct contact of adjacent worksheet strips with each other, said apertures being marginal notches in the carbon strip, and a plurality of spaced fastening means applied to the worksheet strips within said zones, said cut-outs and the means therein being both wholly located between lines of severance. 5

6. A manifolding pile comprising a plurality of continuous worksheet strips and a continuous carbon strip interposed between two adjacent 10 worksheet strips, said strips being separated into form-lengths by weakened lines of severance extending transverse to the pile, the carbon strip having apertures arranged at intervals there- 15 along to provide zones of direct contact of adjacent worksheet strips with each other, said apertures being marginal notches in the carbon strip, and a plurality of spaced fastening means applied to the worksheet strips within said zones, each cut-out being located between two lines of severance to leave carbon strip material at both 20 sides of the securing means in that cut-out.

CARL W. BRENN.
